Filed June 23, 1965, Ser. No. 85,874

Term of patent 14 years

(Cl. D26—14)

FIG. 1

FIG. 2

FIGURE 1 is a front, top and left side perspective view of a stereo loud-speaker unit or similar article, showing my new design in assembled position;

FIGURE 2 is a front, bottom and right side perspective view, the rear being a mirror image of the front; and

FIGURE 3 is an exploded view in perspective showing the opposite face of the individual speakers forming the unit in position for use.

The dominant features of my new design are shown in solid lines in the drawing.

I claim:

The ornamental design for a stereo loud-speaker unit or similar article, substantially as shown and described.
